UNITED STATES PATENT OFFICE

DOMINICK DE PASQUALE AND JOHN L. HOWARD, OF MOUNT VERNON, NEW YORK

STERILIZER AND HOT LIQUID EXTRACTOR

Application filed October 1, 1931. Serial No. 566,364.

This invention relates to a sterilizer for towels and the like, the general object of the invention being to provide a tank containing sterilizing liquid and a drum rotatably arranged in the tank and extending down into the liquid with cables for causing the articles to be sterilized to move around with the drum so that they will be immersed in the liquid and then carried upwardly with the drum under a spring-pressed roller, which removes superfluous liquids from the articles and finally the articles are discharged adjacent the points at which they are introduced into the apparatus.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an end view of the apparatus.

Fig. 2 is a transverse sectional view therethrough.

Fig. 3 is a longitudinal sectional view.

Fig. 4 is a fragmentary front view of the housing.

Fig. 5 is a sectional detail view of the heating element.

Fig. 6 is a transverse sectional view looking in the opposite direction from Fig. 2.

Fig. 7 is a horizontal sectional view through a part of the device showing the hot water pipe.

Fig. 8 is a sectional view through a part of the drum and a part of the roller.

Fig. 9 is a view of one of the pulley supporting members.

Fig. 10 is an end view thereof.

Fig. 11 is a section on the line 11—11 of Fig. 6.

Fig. 12 is a sectional view showing how the rear cross bar is connected to a side member of the frame.

In these drawings, the numeral 1 indicates a tank or housing which is preferably of rec-

tangular shape with its hinged top 1' of semi-circular shape and said tank or housing has in its front an elongated opening 2 for the introduction of the articles to be sterilized, and an elongated slot 3 for the discharge of said articles.

A hinged shelf 4 is located below the slot 2, and is supported in operative position by the pivoted leg 4'. Upper and lower downwardly sloping plates 5 are located on the interior face of the front wall of the housing above and below the slot 2, and upwardly extending plates 6 extend from the upper and lower edges of the slot 3.

A frame 7 is located in the tank or housing and is composed of the two side plates 7', of the shape shown, connected together by the upper cross bar 28, the rear cross bar 28' and the two front cross bars 18. A shaft 9 is journaled in said frame and supports a drum 10. One end of the drum carries a ring gear 11 with which meshes a pinion 12 on the shaft 13 of a motor supported from the frame and located in a small casing 15 at one end of the housing, and the circuit of which is controlled by suitable switches. Thus when the circuit of the motor is closed, the motor will rotate the drum.

Four pulleys 19 are carried by the bars 18 and four pulleys 20 are carried by the brackets 17 connected to the ends of the bars 18. The pulleys are arranged as shown in Fig. 3.

A pair of cables 21 pass around the drum and these cables pass over the guide pulleys 19 and 20 as shown in Fig. 3 so that the cables as they pass over the pulleys are caused to travel away from each other, thus leaving a wide space between the cables at the front of the drum so that articles introduced through the slot 2 and discharged from the slot 3, can pass to and from the drum without interference on the part of the cables. As the cables contact the drum over the greater part of the circumference thereof, said cables will travel with the drum.

Curved arms 22 are pivoted to the frame, one adjacent each end of the housing as shown at 23 and a roller 24 has its pintles journaled in the free ends of these arms.

This roller is formed with a pair of annular grooves 25 through which cables 21 pass and a spring member 26 has its ends engaging the arms 22 for pressing the roller 24 yieldingly against the drum. The tension of this spring is adjusted by means of a set screw 27 which passes through the top bar 28 of the frame 27.

An electric heating element 29 passes into 10 the lower part of the housing through one end thereof, and a thermostat device 30 is associated with this element for automatically controlling the heating of the liquid in the housing. A sight gauge 31 is in communication with the lower part of the housing to show the liquid level therein. A thermometer may be associated with this sight gauge to indicate the temperature of the liquid within the same.

20 A small tank or chamber 33 is located in the bottom of the housing, and coils 34 of tubing are connected to this small tank as shown at 34', the other end of the tubing being connected to an outlet pipe 35 which 25 contains a valve 36, this pipe leading to a sink or other point of use. These coils 34 are located in the housing 1 and rest upon the top of the small tank 33 so that the water passing from the tank 33 through these 30 coils to the point of use and the water passing through these coils is heated by the hot water in the housing when the electric heating means 29 is in use. A supply pipe 37 containing a valve 38 is connected in the tank 33. The lower fitting 39 of the gauge is 35 formed with an extension which is in communication with tank 33 by a connection 37' and with the bottom of housing 1 by a connection 35' and said fitting 39 has a drain 40 valve 40 at its bottom for draining both tanks and valve 41 in the fitting when open will permit water from tank 33 to enter housing 1 to replace the evaporation of water in housing 1.

45 The towels or other articles to be sterilized are dropped into the device through the slot 2 and the plates 5 will direct them into the space between the forward part of the drum and the cables where the cables are directed outwardly by the pulleys 19 and 20. The rotating drum will move the articles to a position where they will be received between the cables and the drum and thus 50 caused to move with the drum. Thus the articles will be carried through the sterilizing liquid and then will pass upwardly with the drum under the pressure roller 24 where superfluous liquid will be removed and finally the articles will engage the lower plate 6 which will remove the articles from the drum and direct them through the slot 3 and to the shelf 4.

55 The coil of tubing in the small tank will provide a supply of hot water, when the

electric heating element 29 is in use, for a sink or the like, though it will be understood that the device can be used with the sterilizing liquid hot or cold.

When desired, a sterilizing preparation 70 can be introduced into the water in the housing by lifting the hinged top.

It is thought from the foregoing description that the advantages and novel features of the invention will be readily apparent. 75

It is to be understood that changes may be made in the construction and in the combination and arrangement of the several parts provided that such changes fall within the scope of the appended claims. 80

Having thus described our invention, what we claim as new is:—

1. A sterilizing device of the class described comprising a housing containing a sterilizing liquid, a drum rotatably arranged in the housing, means for rotating the drum, cables encircling the drum, means for spacing the cables from the front part of the drum, the front of the housing having inlet and outlet openings therein, the inlet opening permitting the articles to be placed between the drum and cables whereby they will be gripped by the cables so as to travel around with the drum, and a spring pressed roller engaging the top of the drum for removing superfluous liquids therefrom, and a deflector plate at the front of the drum for removing articles therefrom and discharging them through the outlet opening. 90

2. A device of the class described comprising a housing containing a sterilizing liquid, a drum rotatably supported in the housing, said housing having inlet and outlet openings at its front, cables passing around the drum, supporting means in front of the drum, pulleys carried thereby and over which the cables pass which space the cables from the front of the drum, said pulleys being so arranged as to space the cables a greater distance apart at the front of the drum 100 than on other parts of the drum, a plate extending downwardly from the lower edge of the inlet opening for directing articles between the cables and the drum, a plate extending upwardly from the lower edge of 105 the outlet opening for removing articles from the drum and causing them to pass through the outlet opening. 115

3. A device of the class described comprising a housing containing a sterilizing liquid, 120 a drum rotatably supported in the housing, said housing having inlet and outlet openings at its front, cables passing around the drum, supporting means in front of the drum, pulleys carried thereby and over which the cables pass which space the cables from the front of the drum, said pulleys being so arranged as to space the cables a greater distance apart at the front of the drum than on other parts of the drum, a plate extending 125

downwardly from the lower edge of the inlet opening for directing articles between the cables and the drum, a plate extending upwardly from the lower edge of the outlet opening for removing articles from the drum and causing them to pass through the outlet opening, a spring pressed roller engaging the top of the drum for removing superfluous liquid from the articles, and electric means

5 for heating the liquid in the housing.

4. A device of the class described comprising a housing containing a sterilizing liquid, a drum rotatably supported in the housing, said housing having inlet and outlet openings at its front, cables passing around the drum, supporting means in front of the drum, pulleys carried thereby and over which the cables pass which space the cables from the front of the drum, said pulleys

15 being so arranged as to space the cables a greater distance apart at the front of the drum than on other parts of the drum, a plate extending downwardly from the lower edge of the inlet opening for directing articles

20 between the cables and the drum, a plate extending upwardly from the lower edge of the outlet opening for removing articles from the drum and causing them to pass through said openings, a spring pressed roller engaging the top of the drum for removing superfluous liquid from the articles, electric means for heating the liquid in the housing, and a small tank in the bottom of the housing, means for supplying water to the same,

25 a coil connected to the small tank, and located in the liquid in the housing, and a discharge pipe connected with the coil.

5. A device of the class described comprising a housing containing a sterilizing liquid, a drum rotatably supported in the housing, said housing having inlet and outlet openings at its front, cables passing around the drum, supporting means in front of the drum, pulleys carried thereby and over which the cables pass which space the cables from the front of the drum, said pulleys being so arranged as to space the cables a greater distance apart at the front of the drum than on other parts of the drum, a plate extending downwardly from the lower edge of the inlet opening for directing articles between the cables and the drum, a plate extending upwardly from the lower edge of the outlet openings for removing articles from the drum and causing them to pass through the said openings, a spring pressed roller engaging the top of the drum for removing superfluous liquid from the

50 articles, electric means for heating the liquid in the housing, a small tank in the bottom of the housing, means for supplying water to the same, a coil connected to the small tank and located in the liquid in the housing, a discharge pipe connected with the coil, and

a valve connection between the small tank and the housing.

In testimony whereof we affix our signatures.

DOMINICK DE PASQUALE. 70
JOHN L. HOWARD.
